UNITED STATES PATENT OFFICE.

DARRELL F. DYKE, OF CHICAGO, ILLINOIS, ASSIGNOR TO THE SENG COMPANY, A CORPORATION OF ILLINOIS.

SOFA BED.

Application filed November 3, 1917, Serial No. 200,019. Renewed April 23, 1919. Serial No. 292,172.

To all whom it may concern:

Be it known that I, DARRELL F. DYKE, a citizen of the United States, residing at Chicago, in the county of Cook and State of Illinois, have invented a new and useful Improvement in Sofa Beds, of which the following is a specification.

My invention relates to improvements in sofa-beds, and has particular relation to improvements upon that construction of sofa-bed for which I filed an application for patent August 18, 1916, Serial No. 115,600.

The objects of my present invention are to simplify and do away with certain details of the construction shown in the above mentioned application, and to provide for the assembling of the parts in the sofa-frame in a convenient manner, and also for their shipment.

Other objects and advantages of the invention will hereinafter appear, and the novel features thereof will be particularly pointed out in the claims.

Referring to the drawings—

Fig. 1, is an elevation of a sofa-bed embodying my invention, one end of the sofa-frame being removed, and the bed-frame or mattress-support being illustrated as opened and ready for use as a bed;

Fig. 2, is a detail in front elevation of one of the sofa-ends;

Fig. 3 is a similar view of one of the sofa-ends in side elevation;

Fig. 4 is a view similar to Fig. 1, the bed being folded and the parts in position for use as a sofa;

Fig. 5 is a detail in elevation of one of the link carrying-plates; and

Fig. 6 is a detail in elevation of the lower end of one of the bed-supporting links.

Similar numerals of reference indicate similar parts in all the figures of the drawings.

It will be understood that I have herein illustrated the conventional form of sofa-frame, and therefore the same comprises the opposite sofa-ends 1. These ends, it will be understood, are connected as is usual at their rear sides, and there is also included in the construction any desired form of movable back, the latter being capable of being raised to permit of the unfolding of the mattress-support or bed and also of be-

ing lowered to engage with the seat when the latter is in its normal position. As these parts form no part of my invention, they have been omitted in the illustrations.

The mattress-support, in this instance, consists of the inner head-section 2, the outer foot-section 3, and the intermediate connecting section 4, the ends of the latter being pivoted as at 5 to the adjacent ends of the two sections 2 and 3, so that as is usual in this class of beds, the foot-section is capable of being folded rearwardly upon and over the head-section and combining therewith to produce a rectangular intermediate space for the accommodation of the bedding.

The seat 6 is invertible in front of the sofa-frame and is provided at its rear edge with an upwardly disposed pair of legs 7, which when the seat is inverted in front of the sofa-frame rest upon the floor and support the front of the seat together with the parts carried by the latter. The front edge of the seat is provided with a depending front board 8, which board fills a portion of the space between the sofa-ends and below the seat when the latter occupies its normal position. To the inner face of the board 8, is secured near each end of the seat a bracket-plate 9, of somewhat greater depth than the board.

Secured to the inner face of each of the front posts 10 of the sofa-ends 1 is an upwardly disposed hook 11, formed on a base-plate 12 having suitable perforations for the reception of screws by means of which said base-plate is secured in position upon the post.

The front board 13 of the sofa-frame is of such length as to fit between the front posts 10 of the companion ends 1 but is disconnected from said posts, and of such width as to complete the filling of the space below the board 8 of the seat 6.

To the inner face of the board 13, and at each end of the same, is secured by bolts or screws, a flanged link-plate 14, (for detail of which see Fig. 5,) said plate being provided at its upper end with an inclined extension 15 forming a guide, which engages a supporting link 29 on one side of the mattress support, the two guides confining the supporting parts between them to prevent

side swaying or wabbling of the mattress support and below the guide with an elongated somewhat pear-shaped opening 16. These plates being rigidly secured to the board 13 are adapted to removably engage over the hooks 11, the latter passing through and interlocking with the openings 16 just referred to. Each plate 14 near its lower end is provided with a bolt-hole 17, and the latter coincides with a similar hole 18 formed in the adjacent sofa-end 1. Through these holes is passed a securing bolt 19, at the inner end of which is threaded preferably a winged-nut 20. By tightening the nut upon the bolt after the plates are engaged by the hook said plates and the front board 13 become rigidly though detachably mounted in position in the sofa-frame.

Pivoted as at 21, at their lower ends and at points near the lower ends of the plates 14 and at the inner sides of the same, is a pair of vertically disposed bell-crank levers 22, which when elevated project above and in front of the board 13. The front ends of these levers 22 are pivoted, as at 23, to short links 24, the front ends of the latter being pivoted as at 25, to the brackets 9 of the seat 6. In rear of the bell-crank levers there are pivoted to the brackets 14, as at 26, links 27, to the upper ends of which there are pivoted as at 28, somewhat longer equalizing links 29, the opposite ends of which are pivoted as at 30, to the brackets 9, of the seat eccentrically with relation to the points of pivot of the links 24. The equalizing links 29 intersect or cross the bell-crank levers 22, adjacent the angles of the latter and at such points said links and bell-crank levers are pivoted together as at 31. There are also pivoted to the plates 14, intermediate the bell-crank levers 22, and the links 27, as at 32, intermediate bed-supporting links 33, the same projecting above the plates 14, and pivoted as at 34, to the inner or head-section of the mattress support at an intermediate point of the same. These supporting-links 33, are provided adjacent their middles with apertured projections 35, to each of which is attached the front end of a coiled-spring 36, the rear end of the spring being engaged by an aperture formed in the upper end of an adjacent supporting-bracket 37, one of which is secured by screws 38, to each of the ends 1 of the sofa-frame. The brackets 37, have their upper ends angularly bent, as at 39, said brackets being in the same horizontal plane and serving as supports for the rear end of the upholstered seat 6, when the latter occupies its normal position, the front end of the seat being supported by the front board 13, upon the upper end of which the depending extension 8, of the seat rests.

To each of the ends 1, near its bottom and

in front of the supporting-brackets 37, is secured a substantially rectangular plate 40, the same being held in position by means of screws passed through suitable perforations in the plate. Each plate is provided near its lower edge with a stud 41, and below the same and in rear with a stop 42, a corresponding stop 43, also being formed at the upper front corner of the plate. A pair of rear supporting-links 44, are pivoted as at 45, to the opposite sides of the rear or head-section 2, near the rear end of the latter, and have their lower ends provided with slots 46, which removably engage and are designed to be pivotally mounted upon the studs 41, of the plates 40. Any desired means may be employed for securing the links 44 upon the studs, but in the present instance, I pivot, as at 47, to each of the links 44 and above their lower ends, a gravity locking-dog 48, the lower end of which at one side is provided with a slot 49, which intersects and is at a right angle to the slot 46 of the link. This dog 48 may be provided at one side with a lug 50, for conveniently operating the same. The links 44 being in engagement with the studs 41, in order to secure said links against accidental disconnection, it is simply necessary to swing the dogs 48 to their lower vertical positions, whereby their slots disposed at right angles to the slots 46 of the links, are caused to engage the studs 41. The stops 42 of the plates 40 serve to limit the downward movements of the links 44, and the stops 43 of said plates, in a similar manner serve to limit the vertical movements of said links.

Pairs of front suspension-links 51 are pivoted at their upper ends as at 52 to the opposite sides of the foot-section 3 of the mattress-support, and at their lower ends, as at 53 to brackets 54, secured to the underside of the sofa-seat, said links aiding in the support of said foot-section. Similar inclined links 55 are pivoted at their upper ends, as at 56, to the opposite sides of the intermediate mattress-section, and at their lower ends as at 57 to brackets 58, secured to the underside of the seat 6 in rear of the brackets 54, and serve to aid in the support of said intermediate section.

59 designates an arched transverse brace, the ends of which are rigidly secured to the intermediate mattress supporting-section 4. The intermediate or arched portion of this brace extends below the mattress-support when the latter is in its operative position and rests upon the links 24 heretofore mentioned, so that said brace forms an additional support for the middle of the bed. When the bed is folded, (as shown in Fig. 4), the arched brace 59 preferably rests in depending stirrups or rests 60, of which there is a pair attached to the front board 13.

of the sofa-frame. These stirrups at their upper ends overlap the securing flanges of the plates 14, so that the same screws employed for holding the plates 14 in position 5 against the board 13 may be utilized to secure the stirrups 60. The stirrups extend below the plates and constitute efficient supports for the front portion of the mattress-support when the latter is in its folded position 10 (see Fig. 4).

If desired, this structure may be augmented by any convenient form of folding head-rest, the same preferably being of such design as will tend to retain the mattress and 15 other bedding while the mattress-support is being folded and unfolded.

In the present instance, short vertical standards 61, formed of angle-iron are secured to one or both of the side bars of the 20 foot-section 3, and mounted in apertures formed in the standards are the lower bent ends 62, of a swinging bail 63, of wire. This bail has internal braces 64, the middle 25 of which is extended as at 65, and connected to a coiled spring 66, the lower end of which spring is connected to the side bar of the foot-section. By swinging the bail to either side of its axial bearing the spring will serve to retain the same in that position. Hence 30 if the bail is swung to a vertical position it will serve as a head-rest, and when in its lowered position it will serve to clamp and retain the bedding upon the mattress-support.

35 Taking the parts in their folded position, as shown in Fig. 4, it will be seen that, as before stated, the seat 6 rests upon the supporting-brackets 39 and the front board 13. To open the bed it is simply necessary to 40 grasp the rear portion of the seat and give it an initial upward impulse, whereupon the linkage system described, assisted by the coiled springs 36 will begin to operate. During this movement, the supporting-links 45 32 and 44, leave their lower positions and swing upward, carrying the bed structure with them, such swinging movements of the links continuing until the rear links 44 abut against the stops 43, at which time said rear 50 links will be in substantially a vertical position and the links 33 slightly inclined forward. The movement of the seat being continued, the remaining sections of the mattress-support will unfold until they assume 55 a position in the same plane as the head-section. As this second step in the operation of unfolding the bed takes place, the bell-crank levers and links 27 swinging on their pivots 21 and 26, respectively, move 60 upward, and by reason of the eccentric relation between the pivots 25 and 30, the seat 6 is completely inverted. The links 51 and 55 swing to their supporting position until 65 the supporting-legs 7 of the seat reach the floor, at which time the upper edge of the

extension 8 of the seat abuts against the under sides of the equalizing links 29, whereupon further movement is arrested.

It will be apparent that by disconnecting the plates 14 from the ends 1, in the manner 70 heretofore described, and likewise disconnecting the supporting-links 44 from the brackets 40, the mattress-supporting frame and its operating links may be compactly folded upon and secured to the sofa-seat and 75 shipped in this condition. The sofa-frame itself may be constructed in knocked-down manner, so that the entire structure will occupy but little space during shipment.

Having described my invention, what I 80 claim is:

1. In a sofa-bed, the combination with the sofa-frame, and a sofa seat invertible in front of the frame, of plates detachably connected to the ends of the frame, a front 85 board rigidly connecting said plates, means carried by the plates adapted to invert the sofa-seat as the same is swung into and out of the sofa-frame, a folding mattress support, and means for raising, lowering, and supporting the same, said mattress-support comprising supporting-links pivotally connected to said plates and operatively connected to said seat.

2. In a sofa-bed, the combination with 90 the sofa-frame, and a seat adapted to be inverted in front of the same, of hooks secured to the opposite ends of the sofa-frame, opposite plates removable engaging said hooks, 95 bolts removably connecting the plates and sofa-ends, mechanism carried by said plates and connected to the seat and adapted to invert the latter when swung into and out of the sofa-frame, a foldable mattress-support, 100 links between the same and the seat, mechanism carried by the plates and connected to the mattress-support, and adapted to guide the same, and a connecting-board permanently secured to the plates and by the latter 105 secured to the sofa ends.

3. In a sofa-bed, the combination with a frame, having depending stirrups, of an invertible seat, a superimposed foldable mattress-support, mechanism for turning the seat as the same is swung into and out of the frame, suspension means between the seat and the frame and the mattress-support, and an arched brace connecting the opposite sides of the mattress support and depending 115 from the same and adapted when the mattress-support is folded to rest in said stirrups.

4. In a sofa-bed, the combination with the sofa-frame, and an invertible seat, of a superimposed foldable mattress-support, connections between the same and the seat and the frame, stirrups depending from the frame, a system of links connected to the frame and seat and adapted to turn the same, and an arched brace connecting the 125 130

opposite side-bars of the mattress-support and adapted when the mattress-support is unfolded to rest upon the system of links and when folded to rest within the depending stirrups.

5. In a sofa-bed, the combination with the sofa-frame, of a foldable mattress-support detachably connected with the frame, rear plates connected to the sofa-ends and provided with upper and lower stops and an intermediate stud, and links connected to the mattress support and having their lower ends slotted to removably engage said studs, and provided above their ends with pivoted 10 dogs having slots at an angle to the slots of the links and adapted to engage said studs.

6. In a sofa-bed the combination with the sofa-frame, and a movable seat, of opposite 20 plates secured to the sofa-ends and provided with upwardly disposed extensions forming guides, a link system connected to the plates and to the seat and adapted to turn the latter and confined between said guides, a 25 superimposed folding mattress-support, and means for connecting the same to the seat and to the sofa-frame.

7. In a sofa-bed, the combination with the sofa-frame, and a seat independent of the 30 same, of a mattress-support connected to and adapted to unfold above the seat as the latter is swung outward and inverted, mechanism for guiding the mattress-support as it is folded and unfolded, a pair of plates 35 having means for detachably securing them to the sofa-ends and carrying said mechanism, a front-board which remains fixed as the mattress-support and seat are folded and unfolded connecting said plates, interposed 40 between and serving to connect the sofa-ends, and means carried by the plates adapted to turn the seat as the same is moved in and out of the sofa-frame.

8. In a sofa-bed, the combination with the 45 sofa-frame, of a foldable mattress-support detachably connected with the frame, opposite rear plates connected to the sofa-ends and each provided with angularly disposed stops projecting therefrom, and links connected pivotally to the mattress-support and 50 removably pivoted at their lower ends to the plates between the stops.

9. In a sofa-bed, the combination with a 55 sofa-frame, a rest depending from the sofa-frame, and a mattress-support adapted to fold within the sofa-frame, of a cross-brace connecting the opposite sides of the mattress-support and adapted when the mattress-support is folded into the sofa-frame to become 60 seated in said rest.

10. In a sofa bed, the combination with a 65 frame having spaced ends unconnected at the front, of supporting hooks at the inner sides of the frame ends, a front board, plates rigidly connected to the ends of the front

board each projecting rearwardly therefrom and having an opening to be engaged by one of the hooks, a sofa seat hinged solely in the end plates and invertible in front of the frame, a folding mattress support comprising sections and links connecting the sections to the underside of the seat to the end plates and to the sofa frame ends for raising, lowering and supporting the mattress support.

11. In a sofa bed, the combination with end frames connected at the back but not at the front, a sofa seat and hinges therefor, a folding mattress support and links connected thereto, and means comprising a pair of end plates connected at the ends of a front board before inserting it in the frame and to which the seat hinges and one pair of the supporting links are connected, and means for detachably but rigidly connecting the end plates to the frame ends so that the front board will be held rigidly in position when the seat is inverted over the front board, in front of the frame to extend the folding mattress support, the seat and front board being bodily attached and removed with the mattress support.

12. In a sofa frame, the combination with a sofa frame consisting of spaced end frames connected at the back but not at the front, a sofa seat, a sectional folding mattress support including supporting links, a pair of hinges for the seat, and means separately connected to the hinges and to the mattress support by a pair of links thereof, for mounting the seat and the mattress support in the sofa frame, said means comprising a pair of end plates, a front board rigidly connected to the end plates before they are inserted in the frame, and means for detachably but positively connecting the plates at the front of the sofa frame so that the front board will be held rigidly in position at the front of the sofa frame without direct attachment thereto.

13. In a sofa-bed, the combination with a sofa-frame, of a sectional folding bed bottom comprising a plurality of sections, a pair of side plates detachably connected to the soft-ends, supporting links for the sections, one pair of which has end slots and hinged locking dogs each with a slot at an angle to the end slot for making a detachable connection with the ends of the sofa-frame, and another pair of which is pivotally connected to the plates, and means attached to the other links and to the plates for folding and unfolding the bed sections.

14. In a sofa-bed, the combination with a frame having spaced ends, of two pairs of supporting plates for attachment to the ends, and a sectional folding bed bottom including two pairs of links pivoted to one section, each separately connected with a supporting plate, one pair of links being

detachably connected to its plates and the other plates being detachable with the links from the frame ends and pivoted links extending from each of the other sections for attachment to the underside of a seat.

15. In a sofa-bed, the combination with a sofa-frame having spaced ends, of a hook projecting inwardly from each end, a detachable folding mattress-support comprising a plate supported at each end by said hook, a front board constituting spacing means rigidly connecting the plates, links attached to the mattress-support having a separate detachable connection with the frame ends, and means connected to such plates and to the mattress-support sections for folding them and extending them from the sofa-frame, the mattress supporting links and said means being bodily attachable and removable from the frame.

16. In a sofa-bed, the combination with the sofa-frame, of a seat invertible at the front of the frame, a sectional mattress frame, means in connection with the seat for raising, lowering, and supporting the mattress-frame, a connection between the frame and the mattress-support comprising a pair of opposite plates each of which is linked to the mattress-support and hinged to the end of the seat, and another link connecting each side of the rear section with the adjacent end of the frame and having a pivoted stop plate attached to the frame with stops thereon for limiting the movement of the links and consequently the mattress frame in both directions.

17. In a sofa-bed, the combination with a frame, of a sectional mattress-support foldable in the frame and adapted to be moved to a horizontal position extending

out of the frame, a pair of links pivotally connected in the frame to each side of the rear mattress-supporting section, a spring at each side of the mattress-support connected at one end to one of the links and 45 at the other end to the sofa-frame, the spring being under tension at all times to ease the mattress-support into and out of the frame, and a stop plate to which the other link at each side of the frame is 50 pivoted for limiting the movement of the link and the extension of the spring in both directions.

18. The combination with a sofa frame having spaced ends, with a hook and a separate pivoting stop plate fixed on the inside of each end; a moveable sofa-seat; and a detachable folding bed bottom comprising a pair of end plates engaging over the hooks, and links detachably connecting the bed 55 bottom to the stop plates, and other links connecting the bed bottom to the end plates and to the seat, for folding and extending the bed bottom when the seat is moved.

19. The combination with a sofa frame, 65 of an invertible seat and fixed rests therefor in the ends of the frame, a sectional folding bed bottom and having links connecting it to the frame ends and to the seat for raising, lowering, and supporting the bed 70 bottom, and a spring connected to the rest and to one of the links at each end of the frame and constantly under tension to assist in raising the seat from the rest and to ease the parts in returning the seat to 75 its position engaging the rests.
